PRESSURE EXERTING MECHANISM

Victor E. Rosenlund, Paxton, and Clarence S. Fuzak, Worcester, Mass., assignors to Reed-Prentice Corporation, Worcester, Mass., a corporation of Massachusetts

Application February 1, 1943, Serial No. 474,382

5 Claims. (Cl. 18—16)

The present invention relates to an improved mechanism for exerting and sustaining pressure between two relatively movable members, such as the dies or molds of a pressure casting machine, or any other machine requiring the development of heavy and sustained pressure between members relatively movable with relation to each other for the performance of a pressing operation.

Pressure exerting mechanisms of this general character, as heretofore constructed, have usually employed operating linkages, working on the toggle principle for actuating the movable members of the mechanisms. It has been found that the development of heavy pressures imposes severe strains on the pivots and connecting elements of such linkages, with resulting breakages of the linkage parts and wear in the pivots, unless the entire mechanism is of very heavy construction.

According to the present invention, there is provided an improved pressure exerting mechanism, characterized by the provision of elements for actuating the movable members that operate with a sliding action during the major portion of the travel of the latter, without the development of pressure, followed by shifting of these actuating elements into pressure exerting position as the relatively movable members come into contact. Such shifting of the actuating elements is accompanied by their wedging engagement with self-aligning abutments mounted on a fixed member, so that heavy pressure is developed and maintained between the relatively movable members with the expenditure of a minimum amount of power. This same self-aligning action of the abutments also permits ready release of the actuating elements preparatory to separation of the pressure exerting members.

The above and other advantageous features of the invention will hereinafter more fully appear from the following description, with reference to the accompanying drawings in which:

Fig. 1 is a longitudinal sectional view of a pressure exerting mechanism embodying the invention.

Fig. 2 is a view similar to Fig. 1, showing the parts of the mechanism in pressure exerting position.

Fig. 3 is a fragmentary view of the pressure exerting parts shown in Fig. 1 in end elevation, and on an enlarged scale.

Fig. 4 is a view similar to Fig. 3, showing the parts in pressure exerting position.

Fig. 5 is a fragmentary sectional view along the line 5—5 of Fig. 2, looking in the direction of the arrows.

Fig. 6 is a vertical sectional view along the line 6—6 of Fig. 1.

Fig. 7 is a vertical sectional view along the line 7—7 of Fig. 1.

Referring to the drawings, the machine consists of a frame 1, providing parallel spaced side members 2 connected by an end member 3 on which a fixed die plate 4 is mounted. A second die plate 5 is slidably mounted for movement on the frame through its cooperation with horizontal ways 6 provided by the side members 2. The die plate 5 is thus guided for movement on the frame, so that the surface thereof is maintained in substantially parallel relation with respect to the opposed surface of the fixed die plate 4, and suitable dies, indicated in dotted lines at D, are adapted to be mounted on the plates 4 and 5.

The plate 5 is movable on the ways 6 by means of actuating elements 7, each pivotally connected to the plate 5 at one end by a pin 8, and at its other end to links 9 by a pin 10. The inner ends of the links 9 are connected to a cross head 11 by pins 9a, with the cross head 11 being movable on rods 12 extending between the plate 5 and a yoke 13 adjustably mounted within the frame 1, as will be later described.

The yoke 13 provides a cylinder 14, and a piston 15 movable within the cylinder 14, provides a rod 16 connected at its end to the cross head 11. The piston 15 is adapted to be moved back and forth within the cylinder 14 through control of the admission of a fluid pressure medium, and when the piston 15 is in the left-hand end of the cylinder as shown in Fig. 1, the actuating elements 7 are maintained in substantially parallel relation within the yoke 13, with the dies D open. When the piston 15 is moved to the right for the die closing operation, the cross head 11 moves the elements 7 directly, with flat surfaces 17 on the elements bearing on parallel ways 18 provided on the inside of the yoke 13. As the die on the movable plate 5 nears engagement with the die on the fixed plate 4, the elements 7 reach the ends of the ways 18 and are then free to swing outwardly with respect to wedging abutments 19 mounted at the end of the yoke.

As best shown in Figs. 3 and 4, each abutment 19 is in the form of a block having a semi-cylindrical surface 20 freely received in a correspondingly shaped seat 21 provided in a block 22 secured to the end of the yoke 13 by bolts 23. The abutment 19 is held against longitudinal movement in its seat 21 by end plates 24, see Fig. 5, while at the same time, the abutment is free to turn about its longitudinal axis X—X. That

portion of the abutment 19 which extends beyond the seat provides a flat surface 25 that is adapted to cooperate with a corresponding flat surface 26 provided by a shoe 27 of hardened metal carried at the free end of an element 7.

When the elements 7 are in their retracted position within the yoke, with the dies separated, it is to be noted that each abutment 19 is maintained in the position of Fig. 3 by a spring 28 connected to each end of the abutment, with the ends of the springs 28 being anchored in lugs 29 provided by the yoke 13. Since the central axis of each spring 28 passes through the pivotal axis of the abutment 19, each abutment is yieldingly maintained in the position of Fig. 3 at an angle to the ways 18 on which the elements 7 slide at the start of the die closing movement.

It is to be noted that the end surface 26 of each shoe 27 at the end of an element 7 has an inclination with respect to the guide surface 17, substantially equal to the normal angle of an abutment surface 25. Consequently, as the elements 7 reach the ends of the ways 18, the surfaces 25 and 26 slide into engagement, as indicated in dotted lines in Fig. 4. Since at this point the dies are closed (or substantially so), continued movement of the cross head 11 to the full line position of Fig. 4, will result in a wedging action tending to compress the elements 7 longitudinally, and through them exert a heavy closing pressure on the dies which will be maintained as long as pressure is maintained on the piston 15. As the elements 7 reach their extended position, the abutments 19 are free to turn axially in their seats 21, while at the same time they are rigidly backed up by the blocks 22. The net result is a self-aligning action of each abutment 19 so that the angle of its surface 25 always corresponds with the angle of the cooperating surface 26 on an element 7 during the entire time that these surfaces are in engagement. Therefore, the transmission and maintenance of extremely heavy pressures through the elements 7 is obtained without appreciable wear of the hardened surfaces 25 and 26, such as would occur were the abutments entirely rigid and incapable of turning on their axes.

The above noted self-alignment of the cooperating surfaces of the abutments 19 and actuating elements 7 prevents any jamming of the parts, such as would prevent ready opening of the dies after sustaining heavy pressure during the molding operation. That is to say, when the cross head 11 starts its die-opening movement, the slightest change in the angles of the surfaces 26 as the elements start to move inwardly, will be accompanied by corresponding change in the angles of the cooperating abutment surfaces 25. Therefore, the elements 7 will readily withdraw from engagement with the abutments 19, and as the elements 7 clear the abutments and are retracted within the yoke as shown in Fig. 1, the springs 28 will automatically cause the abutments 19 to return to the position of Fig. 3.

When the elements 7 are in their pressure exerting position, as shown in Figs. 2 and 4, i. e., with the piston 15 at the end of its right-hand movement and the links 9 substantially vertical, the longitudinal axis Y-Y of each link passes through the center of its pivot 8, and the rotational axis X-X of the engaged abutment 19, see Fig. 5. Therefore, there is in effect a solid connection between the rigid abutment block 22 and the movable die plate 5. As a result, the development of high molding pressures within

the material being injected into the dies cannot separate the dies, with the die plate 5 backed up solidly.

While as previously pointed out, the present mechanism is adapted for use in connection with machines other than pressure casting machines, there is shown diagrammatically in Fig. 1, an injection molding device of a type that can be used most advantageously with the present pressure exerting mechanism. Generally speaking, this device consists of a heater 30 for receiving heat-plasticizable material through the operation of a plunger 31 within a feed cylinder 32. Movement of the plunger 31 to the left by a piston 33, operating within a cylinder 34, causes plasticized material to be injected into the dies D at high pressure through an injection nozzle 35. It is to be noted that even though the pressure per square inch developed within the material by movement 20 of the piston 33 may be many times the pressure developed with the cylinder 14, the dies cannot separate, with the actuating elements 7 rigidly backed up by the abutments 19, as seated in the blocks 22.

As previously indicated, the yoke 13, together with the die plate 5, cross head 11 and cylinder 14, is adjustable as a unit within the frame, so that the distance between the die plates 4 and 5 may be varied in order to accommodate dies of 30 different thicknesses. To this end, the cross head 11 is movable on the rods 12 carried by the plate 5 while the yoke 13 is shiftable on the same ways 6 which support the die plate 5. The yoke provides extensions 36, having openings 37 for receiving adjusting screws 38 and a nut 39 in threaded engagement with each screw 38, is mounted on each extension 36, so that turning of the screws 38 will cause relative movement between the screws and the entire yoke assembly. 40 Each screw 38 is connected to an operating shaft 40 rotatably mounted within an opening 41 passing through an end member 42 of the main frame. The end of the shaft 40 carries a worm gear 43, and the shaft together with its screw 38, is locked 45 against axial movement on the frame by a nut 44 and the shoulder 38a between the screw 38 and its shaft. Therefore, rotation of the shaft 40 by means of the worm gear 43, will impart movement to the yoke 13.

The above described construction is duplicated on opposite sides of the yoke, and the worm gears 43 are adapted to be driven in unison by means of a gear reduction motor 45 providing a shaft 46 carrying worms 47 in mesh with the worm gears 55 44.

Operation of the motor 45 is therefore adapted to drive the shafts 40 in unison to shift the entire yoke assembly with respect to the frame, for the purpose of adjusting the distance between the die plates, when it is desired to make a change in the thickness of the dies D. It is to be particularly noted that any such adjustment of the yoke 13 within the frame 1 in no way affects the setup of the pressure exerting mechanism wherein the cross-head 11 is movable on the rods 12 independently of the yoke. That is to say, the die plate 5 is always rigidly backed up by the engaged elements 7 and yoke abutments 19 to prevent separation of the dies entirely irrespective of the distance between the abutments 70 and the die plates 4.

We claim:

1. A pressure exerting and locking mechanism, comprising in combination a stationary member, an abutment turnable about an axis fixed with respect to said stationary member, a movable pres-

sure exerting member, an operating member movable with respect to said abutment, and a locking element pivotally connected to said movable member and to said operating member about axes parallel to said abutment axis, with movement of said operating member serving to swing said element on its pivotal axis into wedging relation with said abutment to maintain said movable member in pressure engagement, accompanied by turning of said abutment with respect to said element.

2. A pressure exerting and locking mechanism, comprising in combination a stationary member, an abutment turnable about an axis fixed with respect to said stationary member, a movable pressure exerting member, an operating member movable with respect to said abutment, and a locking element pivotally connected to said movable member and to said operating member about axes parallel to said abutment axis, with movement of said operating member serving to swing said element on its pivotal axis to dispose its free end into wedging relation with said abutment to maintain said movable member in pressure engagement, accompanied by self alinement of said abutment with respect to the free end of said element as said abutment turns about its axis.

3. A pressure exerting and locking mechanism, comprising in combination a frame, a member movable on said frame, into pressure exerting position, an operating member movable on said frame, an abutment carried by said frame and turnable on an axis at right angles to the movement of said operating member, a locking element pivotally connected to said pressure exerting member and to said operating member about axes parallel to the abutment axis, and means for imparting movement to said operating member on said frame, to swing said element into wedging relation with said abutment and maintain said pressure exerting member in operative position with respect to said frame, accompanied by self-alignment of said abutment as the latter turns on its pivotal axis in response to engagement by said locking element.

4. A pressure exerting and locking mechanism, comprising in combination a frame, a member

movable on said frame, into pressure exerting position, an operating member movable on said frame, an abutment pivotally mounted on said frame and turnable about an axis at right angles to the movement of said operating member, a locking element pivotally connected to said pressure exerting member and to said operating member about axes parallel to the abutment axis, and means for imparting movement to said operating member on said frame to first cause said element to move in a straight line on said frame as said pressure exerting member approaches its operative position and then to swing said element on its pivotal axis into wedging relation with said abutment to maintain said member in pressure exerting position, with said abutment being turnable on its axis as said engagement occurs.

5. A pressure exerting and locking mechanism, comprising in combination a frame, a yoke supported by said frame, a pressure exerting member movable on said frame with relation to said yoke, an operating member movable on said yoke, an abutment pivotally mounted on said yoke and turnable about an axis at right angles to the movement of said operating member, a locking element pivotally connected to said pressure exerting member and to said operating member about axes parallel to the abutment axis, and means for imparting movement to said operating member on said yoke to first cause said element to move in a straight line on said yoke as said pressure exerting member approaches its operative position and then to swing said element on its pivotal axis into wedging relation with said abutment to maintain said member in pressure exerting position, with said abutment being turnable on its axis as said engagement occurs, said yoke, together with said pressure exerting member, said operating member, said abutment and said locking element being adjustable, as a unit, on said frame to determine the initial position of said pressure exerting member, prior to movement of said operating member.
